E. R. Rupfert
WITNESS

UNITED STATES PATENT OFFICE.

ELDRIDGE V. McCULLOCH, OF KANSAS CITY, MISSOURI.

MAGNETIC SANDING DEVICE FOR MOTOR-VEHICLES.

1,257,265.

Specification of Letters Patent. Patented Feb. 19, 1918.

Application filed June 27, 1917. Serial No. 177,352.

To all whom it may concern:

Be it known that I, ELDRIDGE V. McCULLOCH, a citizen of the United States, residing at Kansas City, in the county of Jackson 5 and State of Missouri, have invented new and useful Improvements in Magnetic Sanding Devices for Motor-Vehicles, of which the following is a specification: -

This invention relates to a sanding device 10 which may be applied to motor vehicles and employed to sand the roadway in advance of the wheels of the vehicle.

The primary object of the invention is to provide an electrically operated device for 15 this purpose which may be applied to any of the types of motor vehicles now in common use without altering the construction thereof, or requiring the services of a skilled mechanic for the application of the device.

Another object of the invention is to provide a device of this character which will 20 require comparatively few parts, thus obviating the likelihood of the device getting out of order while in use.

With these and other objects in view, the 25 invention resides in the novel combination and arrangement of parts, which will be hereinafter described and particularly pointed out in the claims.

The preferred embodiment of the invention 30 has been illustrated in the accompanying drawing, although no restriction is necessarily made to the precise details of construction therein shown, as changes, alterations, and modifications, within the 35 scope of the claims may be resorted to when desired.

In the drawing:

Figure 1 is a view in side elevation of a 40 portion of a motor vehicle to which is shown applied the improved sanding device, the electrically operated valves forming a part thereof being shown in normal position in full lines and in dotted lines in position to 45 permit the sand within the sand box to be discharged upon the roadway in advance of the rear wheels of the vehicle.

Fig. 2 is a top plan view of the sanding device, the valves forming a part thereof being 50 shown underlying a portion of the foot boards of an automobile.

Fig. 3 is a vertical transverse section on the line 3-3 of Fig. 1, the sand box being 55 shown in section.

Fig. 4 is a longitudinal sectional view through a portion of one of the discharge

pipes on the sand box and the valve into which the pipe extends.

Fig. 5 is a section on the line 5-5 of Fig. 4.

Like characters of reference denote corresponding parts throughout the several views in the drawing.

Referring now to the drawing in detail, the letter A designates a portion of a motor vehicle wherein the body 10 is mounted upon 65 the rear wheels 11 in the usual manner, with the body 10 having connected therewith foot-boards 12 and a dash 13.

Mounted beneath the body 10 in any suitable manner in advance of the wheels 11 70 are a pair of solenoids arranged in a normally open electric circuit 15 which may be closed by a switch 16 mounted upon the dash 13 in convenient reach of the operator of the machine.

A sand box 17 is arranged within the body 10, preferably beneath the rear seat of the motor vehicle and is provided with a bottom 18 which inclines in opposite directions from the central portion of the box toward 80 its ends to provide within the box, a pair of hoppers 19 which empty into downwardly extending discharge pipes 20 provided at their lower ends with horizontally extending offset portions 21 interposed between the 85 rear wheels 11 of the vehicle and the solenoids 14.

The offset portions 21 of the discharge pipes 20 extend between hollow cylindrical valves 22 which close the open ends of the 90 discharge pipes and are mounted to turn in spaced bearings 23 secured to the underface of the foot-boards 12.

Each valve 22 has adjustably mounted thereon an actuating bar 24 to one end of 95 which is pivotally connected the core of one of the solenoids 14, whereby when the circuit 15 is closed, the valves 22 may be turned in the bearings 23 to a position in which the channel in a nozzle 25 on the valves will 100 register with a discharge opening 26 in the offset portion of the discharge pipe which extends within the valve.

The other end of the actuating bar 24 has 105 connected therewith and with the foot-board beneath which the valve is arranged, a coiled contractile spring 27 which when the switch is operated to break the circuit 15, turns the valve 22 in the bearing 23 to a position in which the channel in the nozzle on the valve 110 is out of registration with the discharge opening 26 in the offset portion of the dis-

charge pipe, thereby interrupting the discharge of sand from the box upon the roadway.

When the device has been applied to a motor vehicle as shown in Fig. 1 in the drawing and the operator of the machine desires to sand the roadway in advance of the rear wheels of the vehicle, the switch upon the dash is operated to close the circuit 15, thus causing the solenoids to turn the valve and swing the nozzles thereon in a downward direction, so that the sand within the box will be discharged upon the roadway in advance of the wheels.

When the sanding of the roadway is no longer necessary, the circuit 15 is broken and the springs 27 rock the valves in the reverse direction, and cause the nozzles thereon to assume their normal position in a plane parallel to the foot-boards 12, thus cutting off the discharge of sand upon the roadway.

From the foregoing description, taken in connection with the accompanying drawing, it is at once apparent that an electrically operated sanding device for motor vehicles has been provided, wherein the nozzles for discharging sand upon the roadway in advance of the rear wheels of the vehicle are normally maintained in an out of the way position beneath the foot-boards of the machine.

Having thus described the invention, what is claimed as new, is:

1. In a device of the class described, a

source of sand supply, discharge pipes leading therefrom, valves into which said pipes extend controlling the discharge of sand therefrom yieldably held against turning movement, and electrical means for turning 40 said valves.

2. In a device of the class described, a source of sand supply, discharge pipes leading therefrom having offset portions at their lower ends provided with discharge openings, valves into which said offset portions extend controlling the discharge of sand from said openings yieldably held against turning movement, bars adjustably mounted on said valves, and electrical means for 50 turning said valves connected with the bars.

3. In a device of the class described, a sand box having a plurality of hoppers therein, discharge pipes leading from said hoppers having offset portions at their lower ends provided with discharge openings, valves into which said offset portions extend mounted for rocking movement, nozzles on said valves to register with the discharge openings in said offset portions when the valves are rocked in one direction, springs connected with the bars normally holding said nozzles out of registration with the discharge openings in said offset portions, and electrical means for causing said nozzles to register with the openings in said offset portions including solenoids having cores pivotally connected with said bars.

In testimony whereof I affix my signature.

ELDRIDGE V. McCULLOCH
